UNITED STATES PATENT OFFICE.

ALEXANDER MICLAUSH, OF CLEVELAND, OHIO.

PORTABLE OIL STOVE.

Application filed November 12, 1921. Serial No. 514,700.

To all whom it may concern:

Be it known that I, ALEXANDER MICLAUSH, a citizen of the United States, residing at Cleveland, in the county of Cuyahoga and State of Ohio, have invented certain new and useful Improvements in Portable Oil Stoves; and I do hereby declare the following to be a full, clear, and exact description of the invention, such as will enable others skilled in the art to which it appertains to make and use the same.

The present invention relates to improvements in oil stoves and aims to provide a novel and highly efficient burner structure for the stove in which the fuel will be pre-heated initially and subsequently mixed with a volume of air and wherein the burner structure involves a main burner portion and an auxiliary or supplemental burner for pre-heating the fuel and aiding in the preparation of the fuel supply and co-mingled air to the main burner portion.

Another object of the invention resides in providing a compact, simple and inexpensive form of burner applicable to a great variety of stoves in which an active and thorough combustion of the fuel will be insured at all times and which will have a high heating capacity.

With the foregoing and other objects in view, the invention will be more fully described hereinafter, and will be more particularly pointed out in the claims appended hereto.

In the drawings, wherein like symbols refer to like or corresponding parts throughout the several views,

Fig. 1 is a vertical sectional view through an improved stove constructed according to the present invention;

Fig. 2 is a plan view with the parts in open position;

Fig. 3 is a fragmentary view in vertical section taken at right angles to Fig. 1;

Fig. 4 is a horizontal sectional view through the burner structure with parts shown in elevation;

Fig. 5 is a vertical sectional view through a portion of the burner;

Fig. 6 is a side view with part shown in section of the burner structure;

Fig. 7 is a plan view thereof with the main burner removed;

Fig. 8 is a section through the retort tube and the regenerating trough;

Fig. 9 is also a sectional view through the retort, trough and passages;

Fig. 10 is likewise a sectional view through the retort and passages;

Fig. 11 is a detail view of the core; 60

Fig. 12 is a similar view of the wick; and,

Fig. 13 is a sectional view of the retort tube.

Referring more particularly to the drawings, 1 designates a base for the stove made from sheet metal or other suitable material and being in the nature of a container or holder for the liquid oil or other fuel, there being a hand pump 2 to put the fuel container under the requisite pressure for raising the oil to the burner above. The top portion of the container at one side is depressed to form a trough or hopper 3 leading to a central filling neck 4 into which the oil or other liquid fuel is poured, a cap 5 normally closing the fuel inlet and being secured to the neck as by screw threading. 70

A tube 6 lies within the holder 1 at one side thereof and is disposed preferably vertically or substantially so with its lower induction end disposed close to the bottom of the holder. The tube 6 passes up through a neck 7 formed in the top of the holder into which is screw threaded or otherwise connected a valve casing 8 connected to, and in communication with, said tube 6. Within the valve casing 8 is a needle valve 9 being controllable by a hand wheel 10 on the exterior. The needle valve functions to control the amount of fuel raised through the tube 6 and delivered to a suitably curved pipe 11 connecting with the valve casing 8 and with a hollow boss 12 of the generator tube 13 which extends approximately diametrically across the cylindrical shell or casing 14 of 90 the stove, this casing being disposed above the holder 1 and being supported in spaced relation above the top portion thereof as by feet 15 providing between such feet spaces for the introduction of air to the burner 100 from beneath.

The main burner structure is indicated at 16 and comprises a number of arms radiating from a central portion which is in communication with the fuel supply. The 105 burner 16 is supported by suitable braces 17 or otherwise. The arms of the burner 16 are provided with numerous perforations 18 to admit of the issuance of a number of fine jets of the vaporized fuel suitably admixed 110

with air to the end that intimate and active combustion of the fuel may occur.

As more particularly illustrated in Fig 3, the main central portion of the burner 16 is in communication from below with a central fuel conduit 19 comprising two legs disposed on opposite sides of an arch 20 which straddles the generating tube 13. The two legs of the fuel conduit are in communication at their lower portions with ports 21 and 22 made diagonally in convergent walls 23 and 24 of a triangular base structure having a base plate 25 for supporting vertical walls 26 and 27 dividing a central flue 28 from a pair of lateral flues 29 and 30, there being openings 31 and 32 to put the central flue in communication with the two lateral flues.

A depressed central trough 33 is disposed centrally above the base plate 25 between the vertical walls 26 and 27 and is suitably supported by such walls, there being slots 34 and 35 made in the side portions of the trough to admit of the escape therethrough of the vaporized and prepared fuel, the fuel being ignited, and the slots comprising burner openings disposed beneath the generator tube 13 for directing the flame beneath the same whereby to preheat and to vaporize the fuel on its way from the fuel holder 1.

The prepared fuel is received into the central flue 28 from the lateral flues 29 and 30 which communicate with curved branch pipes 36 and 37 which both communicate with a common trunk 38 having its receiving end in communication with the mixing chamber 39. This mixing chamber has its lower end open to receive air in suitable quantities and is provided with a pivoted cover plate 40 at its top portion to admit of access for cleaning or for supplying additional quantities of air. The mixing chamber 39 is formed in a head 41 which together with an opposing head 42 provides a support for the generator tube 13.

A tip 43 is provided on the inner end of the generator tube 13 having a minute recess through which the vaporized fuel is caused to issue under pressure in such wise that a partial vacuum is created in the mixing chamber 39 causing the suction of atmospheric air there into for the purpose of mixing the fuel and forming a combustible product.

The end of the generator tube 13 extends beyond a side wall of the stove casing 14 and is provided with a screw plug 45 for purposes of cleaning the tube and to admit of the core 46 which is removably mounted axially within the tube and is provided with projections 47 extending in a variety of directions and being spaced apart and forming suitable abutments for the spiral winding of a wick 48 of asbestos or other suit-

able absorbent material; end projections 47 forming suitable means with which to engage the looped ends of the wick whereby the same is preventing from uncurling itself about the core or straightening longitudinally.

The wick is preferably of such dimensions relative to the core and tube as to form therein a spiral wall progressing from one to the other end of the tube approximately and 75 constraining the fuel to pass in a spiral path through such tube and insure its being brought successively a number of times to the base portion of the tube which is heated to a high temperature by reason of the direct 80 impingement thereagainst of the flame from the burner slots 34 and 35. The inner end of the core 46 is enlarged and provided with slots 49 for the passage of the fuel.

As shown in Fig. 5, a valve 50 of the 85 needle or other type may if desired be provided at the junction of the fuel pipe 11 with the generator tube to further control the amount of fuel directly entering the tube although this is not essential and may be 90 dispensed with in certain instances.

The stove is further provided with an extension shell or casing 51 lying axially above the first mentioned casing 14 and being flanged and shouldered as indicated at 52 95 to extend about and rest upon the upper edge of the first named shell. The parts are preferably hinged together as indicated at 53 in Fig. 2 to permit of the opening of the top as there shown. Within the top 100 shell 51 are provided a number of refractory plates 54, 55 and 56 having inverted frustro-conical perforations 57 therein of varying sizes, the perforations in the lower plate 54 being smaller than those in the 105 next higher plate 55, yet those perforations of the intermediate plate 55 being smaller than the perforations of the top plate. This construction admits of the gradual expansion of the heated product so that the distribution of these products into the surrounding atmosphere is unattended by the objectionable currents and the strong draft induced where the heated air is directly 110 liberated.

The expansion from one plate to another occurs in chambers 58 and 59 provided by spacing the plates apart, the plates being preferably concavo-convex and bulging upwardly to induce the heated currents to seek 120 the perforations and find exit therethrough. Part of the heat will escape through the slots 58^A and 59^A to the spaces 62 and thence through the openings 65. The marginal portions of the plate are suspended by a 125 number of bolts 60 which have their support through sleeves 61 in the top portion of the shell, such marginal portions of the plates having suitable indentations 62 made therein to provide substantially vertical flues 130,

for the passage of heated product therethrough.

The top of the casing 51 is perforated as indicated at 63 to admit of the expanded 5 heat products issuing upwardly therethrough. The stove as a unit may be transported and carried about by the use of a bail or handle 64.

As indicated in Fig. 3, a number of rows 10 of perforations 65 may be provided in the upper shell 51 in registry with the cut-out portions 62 of the plate edges to permit of a lateral or horizontal projection of heated air into the room which the stove occupies.

15 In use, a suitable quantity of fuel being placed in the holder 1 and the pump 2 having been previously used to supply a suitable pressure in the holder, the valves 10 and 50 may be opened to a desirable extent 20 to allow a requisite amount of the fuel to be raised by the pressure through the tube 6 and pipe 11 into the receiving end of the generator tube 13. A supply of kerosene or like fuel may be initially poured in the 25 trough and ignited with a match for the purpose of starting the device. This heat will lap about the generator tube and cause the vaporization of the fuel passing spirally about the wick and such vaporized fuel after 30 escaping about the cone 49 will issue under pressure through the orifice 44 and into the mixing chamber 39 where it will take up a quantity of air.

The mixture thus formed will be carried 35 through the trunk 38 and distributed to the branch pipes 36, 37 and 37^A, being thence carried to the lateral flues 29 and 30 of the base structure. These flues will permit a certain quantity to enter the central flue 28 40 and to issue through the burner slots 34 and 35 where the fuel will become ignited and act in conjunction with the generator tube to supply heat for the continuous vaporization of fuel passing to the burner.

45 In this case, the generator tube 13 becomes a retort which over lies the supplementary burners 34 and 35. It is understood that the main portion of the fuel goes from the lateral flues up through the legs of the 50 burner flue 19 to the main burner 16 and escaping out through the perforations 18 in the arms of the latter is caused to ascend beneath the lowermost refractory plate 54. The plates are thereby highly heated and 55 their refractory nature permits them to absorb high quantities of heat which they will retain long after the burner has been extinguished.

The fuel in the stove may be therefore 60 kept active only for a sufficient period to thoroughly heat the plates, whereupon it may be discontinued without impairing the heat which will be for a long time subsequently given off by the radiating of the 65 residual heat in the refractory plates. If it

is desired to use the stove for the heating of soldering irons or other tools, the top casing 51 may be swung down into the position shown in Fig. 2 which will expose the main burner 16, and suitable tool holders may be placed directly thereon or a grating may be supported by the burner and cooking utensils placed thereon.

The stove will find many uses both in heating and in cooking. 75

When the casing 51 is closed it is held in place during transportation by the use of a catch 66.

The trough 33 preferably contains a quantity of asbestos 33', as shown in Figs. 80 8 and 9 to absorb the liquid fuel poured thereon and to maintain the heat for a sufficient time to insure starting of the device. The barrel or tube 13 as shown in Fig. 8 is provided with a screw connection 13' 85 square or angular on its outer faces to fit in a correspondingly formed opening 16' in the standard 17' which supports one end of the tube. A set screw 18' holds the connection 13' securely in place. This construction avoids rotation of the tube 13 when the core 46 is rotated therein for the purpose of cleaning. The teeth or projections 47 on the core, upon rotation, will cut into the carbon within the tube and scrape accumulations 95 from the walls of the same. The enlarged head 49 will draw the carbon out of the tube when the core is removed.

90 It is obvious that various changes and modifications may be made in the details of 100 construction and design of the above specifically described embodiment of this invention without departing from the spirit thereof, such changes and modifications being restricted only by the scope of the following claims: 105

What is claimed is:

1. An improved stove comprising a casing, a burner therein, a generator tube placed to be lapped by the heat of the burner, a 110 core in the tube having projections, and a wick wound spirally about the core and having looped ends engaging certain projections, substantially as described.

2. A portable oil stove comprising a base 115 having a reservoir for the fuel, means to put the reservoir under pressure, a casing supported at an elevation above the base, a burner therein, a retort above the burner in controlled communication with the reservoir, 120 a mixing chamber to receive the fuel from the retort, said burner having lateral flues to receive the prepared fuel from the chamber and a central flue in communication with the lateral flues, said central flue leading to 125 the burner, an upper casing hinged to the first-mentioned casing and having openings in its sides and top, and refractory plates above the burner in the upper casing having perforations therein and spaces therebetween 130

said plates having cut-out portions at the margins in registry with the perforations in the sides of the upper casing, substantially as described.

5. A stove comprising a burner, a source of liquid fuel, a retort heated by the burner and in communication with the fuel source, said retort being long and narrow, detachable caps fitting the ends of the retort, one 10 cap having a spray opening, and a chamber receiving the spray cap and connecting with the interior of the burner, a core removably fitted through the other end of the retort and being detachable with the opposite cap, said core having a slotted head adjacent the spray cap to form a bearing for the core in the retort, said core also having rows of circumferentially and axially spaced projections, and a wick wound spirally 15 about the core and the projections thereon and extending substantially to the retort inner wall to form a spiral passage from end to end of the retort, said wick having its ends engaged with end projections to 20 avoid unraveling thereof, substantially as described.

4. A stove comprising a base having a reservoir for the fuel, means to put the reservoir under pressure, a casing supported 30 at an elevation above the base and having air intake openings in its bottom, a main burner in the casing, a supplementary burner below the main burner, an elongated retort

just above the supplementary burner having a tortuous passage therein in controlled 35 communication with the fuel reservoir, a mixing chamber to receive the vaporized fuel from the retort and having communication with the outside atmosphere, a pair of lateral flues beneath the supplementary burner 40 in connection both with the mixing chamber and main burner, and a central flue communicating with the lateral flues and with the supplementary burner, substantially as 45 described.

5. A portable oil stove comprising a base having a reservoir for fuel, means to put the reservoir under pressure, a casing supported at an elevation above the base and having communication at its bottom portion 50 with the outside atmosphere, main and supplementary burners in the casing, a retort heated by the supplementary burner and in connection with both burners, an upper casing above the first-mentioned casing having openings in its sides and top, perforated dished refractory plates supported above the main burner in the upper casing and being spaced from one another with cut-away portions on their edges in communication with the spaces between the plates, said upper casing having openings in registry with the cut-away portions of the plates, 55 substantially as described.

ALEXANDER MICLAUSH
